UNITED STATES PATENT OFFICE.

REBECCA A. GREENUP, OF ST. LOUIS, MISSOURI.

SAD-IRON HOLDER FOR IRONING-BOARDS.

1,277,912.

Specification of Letters Patent. Patented Sept. 3, 1918.

Application filed January 22, 1917. Serial No. 143,643.

To all whom it may concern:

Be it known that I, REBECCA A. GREENUP, a citizen of the United States, residing at St. Louis, Missouri, have invented a certain new and useful Improvement in Sad-Iron Holders for Ironing-Boards, of which the following is a full, clear, and exact description, such as will enable others skilled in the art to which it appertains to make and use the same, reference being had to the accompanying drawings, forming part of this specification.

My invention relates generally to a rest or holder for the sad irons which are used upon ironing boards, the principal object of my invention being to provide a rest or support having a series of rollers which combine to form, in effect, a rolling surface which when the device is properly applied to a board occupies a slightly inclined position below the ironing surface of the board, thereby enabling the iron to be easily shifted onto or from the supporting device, thus wholly eliminating the labor involved in lifting the iron to and from the ordinary form of supporting rack, the surface of which generally occupies a plane a substantial distance above the plane occupied by the ironing surface of the board.

The iron rest or supporting device contemplated by my invention is intended to be positioned near one end of the ironing board immediately adjacent to the cover or pad which is applied to the board and forms the ironing surface. With the support in this position, the iron can be easily shifted onto or from said support with a sliding movement and without any lifting efforts by the operator.

The members which combine to form a rolling support for the iron are transversely disposed with respect to the length of the ironing board and as said rolling support is slightly inclined downwardly away from the ironing surface, it will be readily understood that very little effort is required to move the iron onto or from said support.

In using a sad iron upon an ironing board, the operator generally arranges the work so that the sad iron can be moved lengthwise of said board, for, by such movement, much more work can be accomplished with a single long stroke of the iron in a given period of time than by a comparatively large number of short strokes or movements transversely of the ironing board, and it is one of the

objects of my invention to locate the supporting device in a position where the iron can be readily and without appreciable effort guided onto the rest at the end of an ironing stroke lengthwise of the board.

With the foregoing and other objects in view, my invention consists in certain novel features of construction and arrangement of parts, hereinafter more fully described, claimed and illustrated in the accompanying drawings, in which—

Figure 1 is a plan view of an ironing board equipped with a sad iron rest or support of my improved construction.

Fig. 2 is an enlarged section taken approximately on the line 2—2 of Fig. 1.

Fig. 3 is an enlarged cross section taken approximately on the line 3—3 of Fig. 2.

Fig. 4 is a cross sectional view similar to Fig. 3 and illustrating a modified construction.

Referring by numerals to the accompanying drawings, 10 designates the ironing board which is of the usual form and construction and applied thereto in the usual manner is a cover or pad 11 which forms an ironing surface, the same being yielding to a certain degree.

In order to receive the sad iron rest or support contemplated by my invention, the ironing board is provided near one end and immediately adjacent to one end of the cover 11 with a substantially rectangular aperture 12. The frame of the rest or support is preferably constructed of metal substantially rectangular in form and comprises four vertically disposed walls 13 which when the device is properly applied for use fit snugly against the edges of the board around the opening 12.

Formed integral with the upper edges of these walls 13 are horizontally disposed marginal flanges 14 which bear directly upon the top surfaces of the board 10. The frame thus constructed is fixed to the ironing board in any suitable manner, preferably by means of screws which pass through the flanges 14 and are seated in the board. The inner one of the flanges 14 of the frame is preferably positioned directly upon the adjacent end of the cover or pad 11 as illustrated in Figs. 1 and 2, and thus the support is positioned so that it will readily receive the iron as it is shifted with a sliding movement off the ironing surface. Likewise, the iron can be easily shifted from the support directly onto the

ironing surface of the board and the work positioned thereupon.

Seated in the side walls of the metal frame are the ends of transversely disposed rods 15 5 and loosely mounted upon each rod is a tube 16. These rods are disposed so that the entire series gradually inclines downward from one end of the frame to the other and away from that end of the frame which is immediately adjacent to the pad or cover 11. Thus, when a sad iron is shifted from the ironing surface onto the rest or support, said iron will by gravity travel down the incline formed by the transversely disposed tubes 16 and come to a position of rest against the outer end of the frame of the device.

In some instances, the support for the iron may be formed of a series of rollers 17, the 20 ends of which are provided with trunnions 18 and the latter being loosely mounted in the side walls of the same. (See Fig. 4).

By virtue of the fact that the inclined series of rollers forming a part of my improved device are disposed below the plane occupied by the top of the ironing board and the ironing surface thereof, a pocket is formed in which the sad iron rests while not in use and when the iron is positioned in the pocket, the board can readily be shifted from one position to another or slightly elevated so as to arrange the work thereupon without disturbing the iron. In other words, it will maintain its position within the pocket even though the board be tilted lengthwise or transversely while positioning the work thereon.

A sad iron support of my improved construction is comparatively simple, can be 40 easily and cheaply manufactured, is adapted for use in connection with all ironing boards, and its use entirely eliminates the labor in-

volved in lifting an iron onto and from a rest or support which occupies a plane which is elevated with respect to the ironing surface of the board. 45

It will be readily understood that minor changes in the size, form and construction of the various parts of my improved flat iron support can be made and substituted 50 for those herein shown and described, without departing from the spirit of my invention, the scope of which is set forth in the appended claims.

I claim:

1. A sad iron holder comprising a frame adapted to be applied to an ironing board, and a plurality of revoluble members arranged in said frame and forming the bottom of the holder, which revoluble members are transversely disposed with respect to the length of the board and said plurality of revoluble members being inclined downwardly away from the ironing surface of the board. 60 65

2. In a sad iron holder for ironing boards, a series of rotatably mounted rollers arranged in a pocket formed in the ironing board, said rollers being transversely disposed with respect to the length of the board to which they are applied. 70

3. A sad iron holder comprising a frame adapted to be applied to an ironing board, and a plurality of revoluble members arranged in said frame and which revoluble members form the bottom of the holder. 75

In testimony whereof I hereunto affix my signature in the presence of two witnesses, this 18th day of January, 1917.

REBECCA A. GREENUP.
